UNITED STATES PATENT OFFICE.

WILLIAM A. RANKIN, OF OAK PARK, ILLINOIS, ASSIGNOR TO EDISON ELECTRIC APPLIANCE COMPANY, INC., A CORPORATION OF NEW YORK.

CURLING IRON.

Application filed November 17, 1922. Serial No. 601,630.

To all whom it may concern:

Be it known that I, WILLIAM A. RANKIN, a citizen of the United States, residing in Oak Park, county of Cook, State of Illinois, have invented certain new and useful Improvements in Curling Irons, of which the following is a specification.

My invention relates to curling irons and has for its object the provision of improvements in curling irons, particularly in connection with the operating means for the clamping members.

With the usual type of curling iron in which the clamping members are pivoted together in the manner of the jaws of a pair of tongs, it is often necessary to move the clamping members almost, if not wholly, to wide open position before the hair is released. Also the hair has a tendency to catch at the pivot. In carrying out my invention, I have provided operating means for the clamping members whereby the hair may be quickly and effectively released. In one form of my invention I have provided operating means whereby the clamping members, as they are separated, are caused to take up a position of parallelism with relation to each other. My invention also comprehends a releasable connection between the two clamping members whereby the cylindrical clamping member may be used alone or in conjunction with other appliances.

For a better understanding of my invention reference should be had to the accompanying drawing in which Fig. 1 is an elevation view of a curling iron embodying my invention; Fig. 2 is a view similar to Fig. 1 showing the various positions of the clamping member; Fig. 3 is a partial vertical section view of Fig. 1; while Fig. 4 is a partial perspective view showing one clamping member partly removed.

Referring to the drawing, I have shown my invention as applied to an electric curling iron, although it obviously has application to various other types of curling irons. In one form of my invention I employ an elongated, cylindrical, heated member 10 forming one of the clamping members of the curling iron and provided with a handle 11. The member 10 is provided in its interior with a suitable electric heating element (not shown) the terminals of which are brought out, for example, in a socket in the end of the handle whereby the heating ele-

ment may be connected through a suitable attachment plug 12 to a source of electrical supply.

Cooperating with the cylindrical member 10 is a clamping member 13 having the usual concave convex section and extending longitudinally of the cylindrical member so as to partially surround the cylindrical member when in engagement therewith. The clamping member 13 may be lifted by means of an operating member 14, shown as a lever, to the right hand end of which the clamping member is pivotally secured by a pivot 15 near the left hand end of the clamping member, the operating member having a pivot 16 on uprights or ears 17 carried by a metallic sleeve 18 fitting loosely on the cylindrical member 10. The sleeve 18 carrying the operating lever 14 and the clamping member 13 may be slipped off the cylindrical member 10 to provide for the use of the cylindrical member alone or for the attachment to the cylindrical member of other appliances, such as a comb.

When in normal operating position, as shown in Figs. 1, 2 and 3, the left hand end of sleeve 18 is inserted for a short distance in a locking member 20 in the form of a sleeve secured in the handle 11 and surrounding the cylindrical member 10, the member 20 being countersunk to receive the end of sleeve 18. The member 20 is provided with a longitudinal recess 21 (Fig. 4) with which a projection 22 on the sleeve 18 is adapted to register, whereby the sleeve is held against rotation on the cylindrical member. An annular locking groove 23 is also provided on member 20, and the lower end of a coil spring 24 surrounding pivot 16 rests in this groove, thus releasably securing the sleeve 18 against longitudinal movement on the cylindrical member. The upper end of spring 24 rests against the left hand end of operating lever 14 so as to force this end of the lever in an upright direction and hence bias the clamping member 13 into engagement with the cylindrical member 10. As shown in the drawing, the spring 24 is formed of a doubled length of wire so that the two ends are uppermost and rest against the operating lever 14, while the lower end of the spring is in the form of a loop having a short transverse arc-shaped portion 25 which seats in the groove 23. The spring 24 therefore performs the double

function of yieldably locking the sleeve 18, together with the operating lever 14 and the clamping member 13, on the cylindrical member and biasing the clamping member into engagement with the cylindrical member. Preferably the left hand end of the cylindrical member adjacent the handle 11 is slightly enlarged so as to fit the sleeve 18 snugly at this point whereby the sleeve is secured firmly in place.

The clamping member 13 is provided with an extension 26 forming the left hand end of the clamping member 13 which extension lies between the supporting ears 17 and below pivot 16. Normally the left hand end of the clamping member is held against the projection 22 by the force of spring 24 applied through the operating arm 14 to the pivot 15 of the clamping member, the right hand end of the clamping member being held at the same time in clamping relation with the cylindrical member 10, as shown in Figs. 1 and 3. As the left hand end of operating lever 14 is depressed the left hand end of the clamping member is lifted first due to the overbalancing action of the greater weight of the portion of the clamping member to the right of pivot 15. The left hand end of the clamping member is thus raised until extension 26 engages pivot 16 or the coils of the spring 24 surrounding the pivot, whereupon the right hand end of the clamping member is lifted. To provide for this upward movement of extension 26 the lower end of spring 24 is provided with a lateral downturned portion. It will be observed that after the extension 26 engages pivot 16 the clamping member moves with the operating lever so that the two move together about the pivot 16. When the clamping member 13 has been moved about pivot 16 to full open position, the extension 26 engages with the upwardly extending right hand end of projection 22 on sleeve 18, as shown in dotted lines in Fig. 2, whereby a further opening movement of the clamping member is prevented. The projection 22 may be made of any height according to the amount of opening desired. Obviously, the opening of the clamping member may also be limited by suitably regulating the length of the clamping member to the left of pivot 15 or, in other words, the length of extension 26, in which case the projection or stop 22 may be adapted only to fit in recess 21 so as to hold sleeve 18 against rotation. A suitable button 27 is provided on the left hand end of the operating lever 14 whereby the operating lever may be conveniently depressed by the thumb of the operator in a well known manner.

As thus constructed and arranged, upon depressing button 27 to remove the curling iron from the hair the inner end of the

clamping member 13 is lifted a short distance before the outer end due to the overhanging weight of the outer end. This action assures the complete release of the hair at this point, thus preventing the catching and pulling of the hair common with the usual type of curling iron having its jaws pivoted in the fashion of a pair of tongs. After the inner end of the clamping member 13 engages pivot 16, the outer end is lifted so that the clamping member may be caused to assume a position parallel with the cylindrical member 10 and spaced a predetermined distance therefrom as shown in Fig. 2. Ample space may be provided when the jaws are in this parallel relation to permit the free removal of the hair from the clamping members. The hair may therefore be completely released to permit its removal by only a small depression of button 27. It will be observed that the clamping member 13 is thus initially given a movement of translation to this parallel position. Upon further depression of button 27 the clamping member is moved to full open position about pivot 16, as previously described.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:

1. A curling iron comprising an elongated member, an operating member movably associated with said elongated member, and a clamping member cooperating with said elongated member pivotally secured intermediate its ends to said operating member, said clamping member being free to move on its pivot when lifted by said operating member.

2. A curling iron comprising an elongated member, an operating member pivotally mounted on said elongated member, a clamping member cooperating with said elongated member pivotally secured intermediate its ends to said operating member, said clamping member being free to move on its pivot with relation to said operating member when lifted by said operating member, and means for limiting the movement of said clamping member with relation to said operating member.

3. A curling iron comprising an elongated member, a clamping member cooperating with said elongated member, a pivoted operating member, a connection between said clamping member and said operating member so arranged that the inner end of said

- clamping member is lifted by said operating member before the outer end, and means for limiting the movement of the inner end of said clamping member to cause the outer end of said clamping member to be lifted by continued movement of said operating member.
4. A curling iron comprising an elongated member, an operating member pivotally mounted on said elongated member, and a clamping member carried by said operating member movable by said operating member into clamping relation with said elongated member said clamping member being pivotally connected at an intermediate point with said operating member, whereby said clamping member may be held in clamping relation with said elongated member by depressing said operating member.
5. A curling iron comprising an elongated member, a clamping member cooperating with said elongated member, a pivoted operating member, a connection between said clamping member and said operating member so arranged that the inner end of said clamping member is lifted by said operating member before the outer end, and means for limiting the movement of the inner end of said clamping member to cause the outer end of said clamping member to be lifted so as to pass through a position of parallelism with said elongated member and thereafter move about the pivot of said operating member in a fixed relation therewith.
6. A curling iron comprising an elongated member, an operating member pivotally associated with said elongated member, a clamping member cooperating with said elongated member pivotally secured intermediate its ends to said operating member, and means for limiting the movement of said clamping member with relation to said operating member so that said clamping member is given movement of translation to a position of parallelism with said elongated member after which said clamping member moves with said operating member.
7. A curling iron comprising an elongated member, an operating member movably associated with said elongated member, a clamping member cooperating with said elongated member pivotally secured intermediate its ends to said operating member, and means for limiting the movement of one end of said clamping member as it is moved by said operating member.
8. A curling iron comprising an elongated member, an operating member carried by said elongated member, a clamping member cooperating with said elongated member pivotally secured to said operating member at a point between the ends of said clamping member but nearer one end than the other, and means for limiting the movement of the end of said clamping member nearer to its pivot so as to cause said clamping member to pass through a position of parallelism with said elongated member when said clamping member is being lifted by said operating member.
9. A curling iron comprising an elongated member, an operating lever mounted on said elongated member, a clamping member cooperating with said elongated member pivotally secured near one end to one end of said operating lever whereby said clamping member can be lifted by depressing the other end of said operating lever, a stop engaged by one end of said clamping member when it is being lifted after which said clamping member moves with said operating lever about the pivot thereof to full open position, and a spring cooperating with said operating lever so as to hold said clamping member normally in engagement with said elongated member.
10. A curling iron comprising an elongated member, an operating member pivotally mounted on said elongated member, a clamping member cooperating with said elongated member pivotally secured intermediate its ends to said operating member, and means for biasing said clamping member into engagement with said elongated member, one end of said clamping member cooperating with the pivot of said operating member so as to limit the movement thereof as said clamping member is moved by said operating member.
11. A curling iron comprising an elongated member, an operating member pivotally mounted on said elongated member, a clamping member carried by said operating member movable thereby into clamping relation with said elongated member, said clamping member being pivotally connected at an intermediate point with said operating member, and a stop for limiting the movement of the inner end of said clamping member in both open and closed positions.
12. A curling iron comprising an elongated member, a pair of brackets carried by said elongated member, an operating member pivotally mounted on said brackets, a clamping member having its inner end extending between said brackets, and a pivotal connection between said operating member and an intermediate point of said clamping member.
13. A curling iron comprising an elongated member, a handle therefor, a support releasably secured to said elongated member, an operating member on said support, and a clamping member cooperating with said elongated member pivotally secured intermediate its ends to said operating member.
14. A curling iron comprising an elongated member, a handle therefor, a support

- detachably mounted on said elongated member, an operating member pivotally mounted on said support, a clamping member carried by said operating member, and a single resilient member securing said support on said elongated member acting on said operating member to hold said clamping member in engagement with said elongated member.
- 10 15. A curling iron comprising an elongated cylindrical member, a handle therefor, a sleeve releasably secured on said cylindrical member, an operating member carried by said sleeve, and a clamping member pivotally secured near its inner end to said operating lever, said inner end having its movement limited by the pivot of said lever.
- 15 16. A curling iron comprising an elongated cylindrical member, a handle therefor, a sleeve detachably secured on said cylindrical member, an operating lever carried by said sleeve, a clamping member pivotally secured near its inner end to said operating lever, said inner end having its movements in an upward direction limited by the pivot of said lever, and resilient means for biasing said clamping member into engagement with said elongated member.
- 20 25 30 35 40 45 50 55
17. A curling iron comprising an elongated cylindrical heated member, a sleeve detachably secured to said heated member, an operating lever carried by said sleeve, a clamping member pivotally secured near its inner end to said operating lever, said inner end having its movement in upward direction limited by the pivot of said lever, and resilient means for biasing said clamping member into engagement with said heated member and securing said sleeve on said heated member.
18. A curling iron comprising an elongated cylindrical member, a sleeve detachably mounted on said cylindrical member, a pair of brackets on said sleeve, an operating lever pivoted between said brackets, a clamping member having its inner end extending between said brackets underneath the pivot of said lever, a pivotal connection between one end of said lever and an intermediate point of said clamping member, and a spring securing said sleeve on said cylindrical member acting on said lever to hold said clamping member in engagement with said cylindrical member.

In witness whereof, I have hereunto set my hand this thirteenth day of November, 1922.

WILLIAM A. RANKIN.
